INFANT'S BOTTLE GUARD OR SIMILAR ARTICLE

Rudy Miller, Brooklyn, N. Y., assignor to Caris-
Art Inc., Brooklyn, N. Y., a corporation of New York

Application June 28, 1950, Serial No. 10,820

Term of patent 3½ years

(Cl. D83—8)

To all whom it may concern:

Be it known that I, Rudy Miller, a citizen of the United States and a resident of Brooklyn, New York, have invented a new, original, and ornamental Design for Infant's Bottle Guard, or Similar Article, of which the following is a specification, reference being had to the accompanying drawing, forming a part hereof, in which

Figure 1 is a side elevational view of an infant's bottle guard, or similar article, showing my new design; and

I claim:

The ornamental design for an infant's bottle guard, or similar article, as shown.

RUDY MILLER.
